[57] **CLAIM**

The ornamental design for a tool holder, as shown and described.

DESCRIPTION

FIG. 1 is perspective view of a tool holder in accordance with the present invention;

FIG. 2 is a top view of the tool holder of the present invention;

FIG. 3 is a bottom view of the tool holder of the present invention;

FIG. 4 is a side elevational view of the tool holder of the present invention, the opposite side being a mirror image thereof.

FIG. 5 is a front view of the tool holder of the present invention; and,

FIG. 6 is a rear view of the tool holder of the present invention.

The broken line showing of environment is for illustrative purposes only and forms no part of the claimed design.
